United States Patent Office.

LEWIS BURGER, OF SPRINGFIELD, ILLINOIS, ASSIGNOR TO HIMSELF AND
ISAAC L. HAMBURGER, OF ALBANY, NEW YORK.

Letters Patent No. 77,450, dated May 5, 1868.

IMPROVEMENT IN DOOR-DIRECTORIES.

The Schedule referred to in these Letters Patent and making part of the same.

TO ALL WHOM IT MAY CONCERN:

Be it known that I, LEWIS BURGER, of Springfield, in the county of Sangamon, and State of Illinois, have invented a new and improved Door-Directory; and I do hereby declare that the following is a full, clear, and exact description thereof, which will enable others skilled in the art to make and use the same, reference being had to the accompanying drawings forming part of this specification.

Figure 1 represents a front elevation of my invention, showing the dial displayed.

Figure 2 is a similar view of the same, the dial being concealed.

Figure 3 is a vertical central section of the same, the plane of section being indicated by the line xx , fig. 1.

Similar letters of reference indicate corresponding parts.

This invention relates to a new indicator or director, to be attached to office or other doors. Its object is to indicate, to parties intending to enter the office, whether the proprietor is in or not, and if not, when he will return, and whither he has gone.

The indicator may be connected with a letter-box, card-holder, and with a slate for orders.

The invention consists in arranging, within a box that is to be attached to the outside of a door, or near the same, a series of rollers, carrying aprons or marked on their edges, the faces of the aprons or the figures on the rollers being displayed through-holes in a dial.

The rollers can be turned and set from the outside, so as to display any one of their marks, and thus the date of return, and the place whither the occupant of the office has gone, can be displayed through the dial. Hands, to indicate the exact time of return, are also arranged upon the dial, and can be set to indicate any desired hour.

The dial is closed by a hinged cover when the occupant is in the office, and when the cover is open it displays a slate on its inner face, upon which orders can be marked.

A represents a box or case, made of wood, metal, or other suitable material, of any suitable dimensions and shape. It is provided with an eye, *a*, by means of which it can be attached to a door or wall, or is otherwise so arranged that it can be thus fixed in position.

Its face or front plate, *B*, is provided with the twelve hour-marks, arranged in a circle to represent a clock-dial. Two hands, *b* and *c*, are arranged in the centre of this circle, and are fitted upon a shaft, *d*, and sleeve, *e*, respectively, the said shaft and sleeve being connected by belts *f* and *g* respectively, or by gear-wheels or otherwise, with shafts *h* and *i*, as shown in fig. 3.

The front ends of the shafts *h* and *i* project through holes in the front of the case, and are squared, so that they can be turned by a key to set the hands.

C is an endless apron, fitted over two rollers, *J* and *K*, and behind a hole in the dial-plate *B*. Upon it are marked the names of the months, and by turning one of the shafts *J* or *K*, by means of a key, the name of the required month can be displayed on the dial.

D is a similar apron, fitted over two rollers, *l* and *m*, and behind a hole in the dial-plate *B*. Upon the apron *D* are marked the figures, 1 to 31, to indicate the day of month. The same can be displayed on the dial.

E is a roller, marked around its periphery with the names of days. It can be turned by the key, so as to display the name of any desired day through the hole in the dial-plate.

F is an apron, fitted around two rollers, *n* and *o*. Upon it are marked notes, indicating whither the proprietor of the office has gone, such as, "Gone to see a patient," or other appropriate marks.

All the rollers or straps hereinbefore mentioned have their bearings in the walls of the box *A*, or in partitions arranged therein, and they are all horizontal.

G is a cover, hinged to the box *A*, so that it can be folded over it, as in fig. 2, to cover the dial-plate, as it can be opened to display the dial-plate. In the latter case the inner face of the cover *G* is displayed. The same is lined with slate, or other suitable material, to allow the writing of orders upon the same.

H is a box, suspended from the lower part of the box A, and having a slotted front, to allow the insertion of letters. A small card-holder, I, can be arranged in front; also, a pencil-holder, J, as shown in figs. 1, 2, and 3.

When the proprietor of the office is in, the cover G is closed over the dial-plate, as shown in fig. 2, and only the sign of the firm is displayed on the box, and a mark on the cover, indicating that the office is open.

When the office is left, the cover G is folded back, as in fig. 2, and can be used for marking orders upon it. The various rollers and aprons and hands are set to indicate the time of day and date when the proprietor will return, also the place whither he has gone.

The dial-plate may, if desired, be protected by a pane of glass, K, as shown.

I claim as new, and desire to secure by Letters Patent—

1. A door-directory, consisting of a box, with perforated dial-plate, A, and of various rollers, aprons, and hands, to indicate time and date of return, and other notes, substantially as herein shown and described, the rollers, aprons, or hands only being adjustable, by means of a suitable key, as described.

2. The combined cover and slate G, when the same is arranged on a door-indicator, substantially as herein shown and described.

3. The letter-box H, card-holder I, and pencil-holder J, when arranged in combination with the door-indicator, all made and operating substantially as and for the purpose herein shown and described.

LEWIS BURGER.
